[57] CLAIM

The ornamental design for a combined vial and supporting base, substantially as shown and described.

DESCRIPTION

FIG. 1 is an exploded perspective view of a combined vial and supporting base showing my new design;

FIG. 2 is a top plan view of the vial;

FIG. 3 is a bottom plan view of the base;

FIG. 4 is a bottom plan view of a vial showing a second embodiment of my new design;

FIG. 5 is a bottom plan view of a vial showing a third embodiment of my new design;

FIG. 6 is a top plan view of the base of the second embodiment;

FIG. 7 is a top plan view of the base of the third embodiment;

FIG. 8 is an elevational view of the vial and base of FIG. 1 with the vial in place;

FIG. 9 is a sectional view taken on the line 9—9 of FIG. 1;

FIG. 10 is an exploded perspective view of the second embodiment; and

FIG. 11 is an exploded perspective view of the third embodiment.

The top of the vial of FIGS. 4 and 5 has the same appearance as the vial top shown in FIG. 2.
